UNITED STATES PATENT OFFICE

CHARLES A. CROWL, OF NEW CASTLE, PENNSYLVANIA, ASSIGNOR, BY MESNE ASSIGNMENTS, TO STEWART P. FOLTZ, OF NEW CASTLE, PENNSYLVANIA, AS TRUSTEE

HEAT EXCHANGER

Application filed June 10, 1932. Serial No. 616,459.

The invention relates to heat exchangers, and more particularly to multiple unit heat exchangers having parallel fluid conducting passages.

It is among the objects of this invention to provide a heat exchanger which has two parallel fluid conducting passages, comprises a plurality of interchangeable doubled-walled fluid-conducting elements connected end to end, is quickly and easily assembled in any desired length, and economically and efficiently produces heat exchange between two fluids flowing therethrough.

In accordance with the invention there is provided a heat exchanger comprising a plurality of double-walled fluid-conducting elements having extended integral rims and connected end to end between two coupling members. Each of these elements is provided with a conduit through it and with a plurality of apertures in its walls forming with the other elements two parallel intertwined zig-zag fluid passages, one passage being disposed in the elements and the other between them.

The invention is illustrated in the accompanying drawing, of which Fig. 1 is an end view of a fluid conducting element; Fig. 2 a side elevation of an assembled heat exchanger shown partly in section, the sectional portion being taken on the plane indicated by line II-II of Fig. 1; and Fig. 3 a view similar to Fig. 2, with the sectional portion taken on the plane indicated by line III-III of Fig. 1.

Referring to the drawing, a plurality of interchangeable fluid conducting elements 1 are disposed end to end with gaskets 2 between them, each end of the structure thus formed being provided with a coupling or end member 3. Elements 1 are retained in position between couplings 3 by rods 4 which pass through the entire structure and are held in place by nuts 5 turned on their threaded ends against the couplings, thereby forcing the elements tightly together and forming a complete heat exchanger.

Each element 1, preferably a one-piece cylindrical casting, has two spaced walls 7 and 8 encircled and connected at their peripheries by an integral annular rim 9 forming with

the walls a chamber 10 within the element. A support 11 reinforces the walls at substantially their centers. Bosses 12, 13, 14, and 15, integral with the rim and the walls, extend through the element at four points equally spaced apart, and form longitudinal apertures 16 through which rods 4 extend. A semi-circular flange 18, projecting outward from wall 7, extends from boss 12 to boss 14 by way of boss 13, and a like flange 19, projecting from wall 8, extends from boss 12 to boss 14 by way of boss 15, the two flanges thus being diagonally opposite each other. Between each of these flanges and the adjacent portions of rim 9 there are two arcuate apertures 21 opening into chamber 10, thereby forming a passage through the element, which is also provided with a conduit 22 extending through it next to boss 15 and flange 19, the conduit being separated from chamber 10 by wall 23 which forms it.

When the elements are placed end to end to form the heat exchanger, each successive element 1 is rotated on its longitudinal axis until its apertures 21 in one wall register with the apertures 21 in the adjacent wall of the preceding element, thus forming a continuous passage from chamber 10 of one element into the corresponding chamber of the other. Therefore, when all of the elements are in proper position each one has been turned axially 180° from the position occupied by the elements adjoining it. The result is that a continuous zigzag passage is formed through chambers 10 and apertures 21 from one end of the unit to the other. Furthermore, turning each successive element 180° brings conduits 22 diagonally opposite each other, instead of in line, and thereby provides another continuous zigzag passage intertwined with the first-mentioned passage, but this one is disposed in part between the adjacent walls of adjoining elements where a chamber 25 is formed by extended ends of rims 9. These two passages are disposed parallel to each other, the two being separated from each other by walls 7 and 8, flanges 18 and 19, and walls 23 of conduits 22.

To permit fluids to be introduced into one

and to be discharged from the other end of each of the continuous passages through the exchanger, the ends of the structure are provided with coupling members 3 which are 5 adapted to be connected to intake and discharge pipes. Each member 3 comprises walls 26 and 27 having an integral annular rim 28 encircling their peripheries and forming with the walls a chamber 29. Like elements 10 1, each end member is provided with bosses 31 having apertures 32 through which the ends of rods 4 extend. A semi-circular flange 33, projecting outward from wall 26, registers with flange 18 of the adjoining element 15 1, there being two arcuate apertures 34 between flange 33 and the adjacent extended portion of rim 28 registering with apertures 21 of the adjoining element. A conduit 35, having a threaded flanged outer end extends 20 through the coupling member to chamber 25, and a flanged threaded aperture 36 in rim 28 opens into chamber 29 diametrically opposite to apertures 34. To conduits 35 and apertures 36 at the ends of the heat exchanger inlet and outlet pipes may be connected for supplying the fluids to and carrying them away from the two parallel passages.

From the foregoing it will be apparent that 30 a fluid, gaseous or liquid, flowing through one passage of the heat exchanger absorbs heat from another higher temperature fluid flowing through the other passage parallel to it, the transfer or exchange of heat being 35 through the walls 7 and 8 of elements 1. The flow of the fluids in the passages may be in the same direction or in opposite directions, depending on which end of each passage is used for the connection of the inlet pipe. 40 However, in all cases the two fluids flow substantially parallel to each other on the opposite sides of walls 7 and 8, which is of material advantage in certain heat exchanging operations, as for example in the cooling of 45 spent pickling acids. The extent of heat exchange or transfer area afforded by each assembled apparatus depends upon the number of elements 1 which are used, each of which is alike, as are the coupling members 50 3. Accordingly, heat exchangers of any size may be assembled from castings of but two different forms.

According to the provisions of the patent statutes, I have explained the principle and 55 mode of operation of my invention, and have illustrated and described what I now consider to represent its best embodiment. However, I desire to have it understood that, within the scope of the appended claims, the invention 60 may be practiced otherwise than as specifically illustrated and described.

I claim:—

1. A heat exchanger comprising a plurality 65 of interchangeable double-walled fluid conducting elements having integral rims

projecting outwardly from the walls connected end to end, each of said elements being provided with a conduit through it and a plurality of apertures in its walls and forming with the other elements two parallel intertwining zigzag fluid passages, one of said passages being disposed in said elements and the other between them, and means for delivering fluids to and discharging them from the respective passages.

2. A heat exchanger comprising a plurality of interchangeable double-walled fluid conducting elements having integral rims projecting outwardly from the walls, each wall of each of said elements being provided with a flanged aperture adjoining the rim and disposed diagonally opposite each other, and each element having a conduit therethrough adjacent said rim, said elements being connected end to end with said flanged apertures thereof registering, a continuous zigzag fluid passage through the elements and a parallel intertwining zigzag passage between them thereby being formed in the heat exchanger, and means for delivering fluids to and discharging them from the respective passages.

In testimony whereof, I sign my name.

CHARLES A. CROWL.
